COAXIAL TRANSMISSION LINE

Lewis A. Bondon, Arlington, N. J.

Application December 26, 1946, Serial No. 718,489

5 Claims. (Cl. 174—28)

1

This invention relates to coaxial transmission lines and has more particular reference to insulating assemblies for maintaining the conductors of such lines in concentric relation.

Conventional forms of coaxial transmission lines usually comprise a tubular inner conductor disposed in a tubular outer conductor and spaced concentrically therefrom by insulating spacing devices. One conventional type of spacing means comprises insulating rings or discs usually made of ceramic material and mounted on the periphery of the inner conductor at intervals therealong. The rings or discs are usually secured on the inner conductor by one of the following means:

(a) Rolled annular beads or expanded shoulders formed on the inner conductor on both sides of the insulating ring; (b) soldered collars on the inner conductor on both sides of the insulating ring; (c) annular springs compressed to fit in undercuts in the discs and inner conductor; (d) annular spring supported locking pins indexing in the inner conductor and with recesses in the discs or rings; and (e) friction.

Another conventional type of spacing means comprises radial insulating rods or pins usually made of ceramic material and secured to the inner conductor at intervals therealong. The rods or pins are usually secured to the inner conductor by one of the following means:

(a) Pins secured by cement to the surface of the inner conductor; (b) pins secured by annular staking at inner conductor; (c) pins supported by outer conductor and not attached to inner conductor; (d) pins secured by threaded inserts in inner conductor; (e) pins supported by supports through their body, then staked to the inner conductor.

All of these assemblies, whether of the insulating ring type or insulating pin type, are deficient for one or more of following reasons:

(a) Large proportions of solid dielectric; (b) sensitive to thermal shocks; (c) undesirable diametric irregularities; (d) poor physical properties; (e) reduced amount of radio frequency conducting surface; (f) unpredictable dielectric stability; (g) difficult to repair after assembly; and (h) costly and difficult to manufacture.

The object of all the foregoing methods of coaxial line construction is to obtain a signal propagating medium having a propagating constant that is close to that provided by air. This propagation constant is reduced as soon as dielectrics having specific inductive capacity values higher than air are introduced into the propagating me-

2

dium. Therefore the desirable coaxial transmission line must have a minimum mass of low dielectric body as supporting and spacing elements as will allow maximum physical and thermal performance under various service conditions for long periods of time without need for replacement or maintenance.

In addition to the foregoing, the inner and outer conductors must be maintained as accurately as possible in concentric relation throughout the transmission system in order to provide undistorted signal propagation from the signal source to the terminating elements. When momentary or sustained high voltage gradients exist along the line it is necessary to have this accurate concentric relation to provide a uniformly distributed electrical stress at the points of support to prevent localized dielectric heating and possible thermal failure and to prevent lower corona initiation voltages producing electrical flash-over at these points and a subsequent inoperative system. At these points of support it is necessary that all air be excluded between the dielectric and the inner conductor, chiefly because the voltage gradient is maximum at these points and will often cause local ionization, thereby reducing the corona initiation voltage of the transmission line as well as introducing distortional effects on the propagating signals.

It is an object of the present invention to provide a coaxial transmission line in which the inner and outer conductors are held in accurate concentric relationship, throughout their length, by longitudinally spaced, angularly disposed insulating spacing assemblies, each of which comprises a pair of diametrically opposed insulating spacing members positioned between the conductors and held in position by an insulating pin passing through the inner conductor with its ends engaging the spacing members.

Another object of the invention is to provide a coaxial transmission line, as characterized above, in which the pins and spacing members are made of insulating material of such character and are assembled in such manner as to provide great resistance to thermal and physical shock.

Another object of the invention is to provide a coaxial transmission line, as characterized above, in which the spacing members and supporting pins are made of insulating materials which provide a propagating medium substantially the same as air, thus providing higher signal transmission efficiency to permit its use at frequencies beyond the range of the conventional air dielectric coaxial transmission line.

Another object of the invention is to provide a coaxial transmission line, as characterized above, in which the supporting pins and the spacing members are made of insulating material of such character and are assembled in such manner as to obviate the necessity for the usual linear dimensional tolerances, thereby providing a differential impedance limit heretofore unobtainable for commercial application.

A further object of the invention is the provision of a coaxial transmission line that can be readily assembled and repaired in both factory and field and one that is relatively inexpensive to manufacture.

Other objects and advantages will be apparent in the following specification, when considered together with the accompanying drawings, in which:

Fig. 1 is an elevational view with parts broken away of a coaxial transmission line constructed in accordance with the present invention;

Fig. 2 is an end view with certain parts shown in section, of the coaxial transmission line shown in Fig. 1;

Fig. 3 is an end view of one of the insulating spacers shown in Figs. 1 and 2; and

Fig. 4 is an elevational view of the insulating spacer shown in Fig. 3.

Referring to Figs. 1 and 2, there is shown a coaxial transmission line comprising an outer conductor 10 and an inner conductor 11. The conductors are held in concentric relationship, throughout their length, by means of longitudinally spaced, angularly disposed insulating spacing assemblies mounted on the inner conductor.

Each insulating assembly comprises a diametrically opposed pair of spacing members or caps 12 interposed between the inner and outer conductors and engaging diametrically opposed sections on the inner surface of the outer conductor and held in position by means of an elongated pin 13 extending through diametrically opposed holes 14-14 formed in the inner conductor with its projecting ends 15-15 press-fitted into recesses 16-16 formed in the caps 12.

Each of the caps 12 is identical in construction and, in the particular embodiment illustrated, is shown as a cylindrical member having a coaxial cylindrical recess 16 provided with a conically shaped bottom 17 formed therein. One end of the cylinder is wedge-shaped, as indicated at 18, and the other end is made concave, as indicated at 19, with a surface curvature the same as the outer surface curvature of the inner conductor. The caps are preferably made of a compressible plastic organic insulating material such as polytetrafluoroethylene. This is an extremely low-loss material. It is physically capable of maintaining operating efficiency at the elevated temperatures encountered in normal service and is also physically capable of maintaining intimate contact with the conducting surface of the inner conductor throughout the service life of the line. Cap members made of this material will not carbon-track on flash-over and do not require surface impregnating treatments to reduce its moisture absorption factor as the material is normally nonhydroscopic.

Each of the pins 13 is identical in construction and in the particular embodiment illustrated is shown as an elongated cylindrical member having conically shaped ends 15-15. The pins are made of an organic insulating material. The material preferred is a thermosetting styrene copolymer such as ethyl vinyl benzine divinyl ben-

zene styrene copolymer. Such a copolymer is disclosed in U. S. Patent No. 2,256,160, issued September 16, 1941. The pins may also be made of methyl methacrylate or of ceramic material composed principally of magnesium oxide. Pins made of the foregoing named materials are not subject to deformation, cracking or plastic flow. They have great resistance to physical shock and are physically capable of maintaining maximum operative efficiency at the elevated temperatures encountered in normal service exposures. The diameters of the pins are such that they fit tightly in the holes 14, 14 formed in the inner conductor to eliminate any air therebetween.

In the preferred construction, the pins are approximately one-half the diameter of the caps and approximately one-fourth the diameter of the inner conductor.

In assembling the transmission line, the supporting pins 13 are fitted in the openings 14, 14 in the inner conductor. Then, the caps 12 with their wedge-shaped ends positioned longitudinally, are press-fitted onto the projecting ends of the pins and against the outer surface of the inner conductor.

The concave end 19 of each cap provides an intimate physical air-tight saddle fit with the outer surface of the inner conductor, as indicated at 20. Then, the inner conductor, with the spacing assemblies in place, is press-fitted into the outer conductor, the plastic material of which the caps are made being slightly compressed to make an intimate physical fit with the inner surface of the outer conductor. To facilitate the insertion of the cap member into the outer conductor, the longitudinal ends of the wedge-shaped end 18 may be bevelled, as indicated at 21.

The insulating assemblies are longitudinally spaced at desired intervals and may be disposed on the inner conductor in any desired angular relation. In the particular embodiment illustrated, they are shown as being angularly disposed 90° relative to adjacent assemblies.

Spacing assemblies employing a combination of extremely low-loss dielectrics, as above set forth, and assembled in the manner described, substantially eliminate all air in the dielectric field at the points of assembly and reduce the flux density in the electric field at these points. The elimination of air in the dielectric field at the points of assembly minimizes the probability of any local corona formation at these points. The low-loss properties of the dielectric combination at any service frequency encountered in the application of an air dielectric transmission line affords stable dielectric performance, which, with the positive centering of the inner conductor, provides a stable and continuously uniform propagating medium free from diametric discontinuities.

The spacing members or caps 12, being made of compressible plastic material press-fitted between the inner and outer conductors, permit the use of dimensional tolerances which cannot be effected with conventional inorganic materials without a large increase in processing cost and subsequent attendant assembly difficulties increasing the final cost.

A coaxial transmission line constructed in accordance with this invention, does not require the usual linear dimensional tolerances, thus providing a differential impedance limit heretofore unobtainable for commercial application. This provision will permit a wider field of application for coaxial transmission lines as such dimensional

Limitations restrict the development of high standing waves to less than 10% of the voltage standing wave ratio introduced at the signal source.

In addition, such a construction provides a minimum signal attenuation for a transmission line of a given impedance. This is due to the low-loss dielectric combination, which will, for a given line impedance, permit the use of a larger center conductor to provide an increase in radio frequency conducting surface with attending increase in power handling capacity.

From the foregoing, it will be seen that there has been provided a coaxial transmission line having an impedance and providing a propagating medium substantially the same as that of a theoretical coaxial transmission line of the same dimensions in which the inner conductor is supported solely by air.

While the invention is particularly described in connection with a coaxial transmission line having a tubular inner conductor, obviously, it is equally well suited to a coaxial transmission line having a solid inner conductor.

Obviously, the invention is not restricted to the particular modifications herein shown and described.

I claim:

1. A coaxial transmission line comprising tubular inner and outer conductors and spacing assemblies radially disposed within said outer conductor at predetermined spaced points throughout its length for maintaining said conductors in concentric relation, each of said assemblies comprising a pair of diametrically opposed insulating members press-fitted between the inner surface of the outer conductor and the outer surface of the inner conductor to provide intimate surface contacts between said insulating members and said inner conductor, said members consisting of polytetrafluoroethylene having coaxial recesses formed therein and an elongated insulating member extending diametrically through said inner conductor and having its ends press-fitted into the recesses formed in said first named members.

2. A coaxial transmission line, as set forth in claim 1, wherein said first named insulating members are cylindrical and have concave inner ends and wedge-shaped outer ends, said concave ends having a curvature substantially the same as the curvature of the outer surface of the inner conductor to provide intimate physical contact therewith, thereby excluding all air therebetween and said wedge-shaped outer ends provide intimate physical contact with the inner surface of the

outer conductor along diametrically opposed longitudinal sections thereof and wherein said elongated insulating member is cylindrical and has its ends contoured to conform to the contour of the inner surfaces of said recesses.

3. A coaxial transmission line, as set forth in claim 1, wherein said elongated member is made of a thermosetting styrene copolymer.

4. A coaxial transmission line, as set forth in claim 1, wherein said elongated member is made of ethyl vinyl benzene divinyl benzene styrene copolymer.

5. A coaxial transmission line comprising tubular inner and outer conductors and spacing assemblies radially disposed within said outer conductor at predetermined spaced points throughout its length for maintaining said conductors in concentric relation, each of said assemblies comprising a pair of diametrically opposed cylindrical cap members provided with coaxial recesses and press-fitted between the inner surface of the outer conductor and the outer surface of the inner conductor, said cap members being made of polytetrafluoroethylene and having concave inner ends to provide intimate physical contact with the outer surface of the inner conductor and wedge-shaped outer ends to provide intimate physical longitudinal line contact with the outer conductor, and an elongated cylindrical pin extending diametrically through said inner conductor and having its ends press-fitted into the recesses formed in said cap members, said pin being made of ethyl vinyl benzene divinyl benzene styrene copolymer and having its ends contoured to conform to the contour of the inner surfaces of said recesses.
